US0D1037875S

(12) **United States Design Patent** (10) Patent No.: **US D1,037,875 S**
(45) Date of Patent: ** Aug. 6, 2024

(54) **SCALE**

(71) Applicant: **Zhongjin Dai**, Dezhou (CN)

(72) Inventor: **Zhongjin Dai**, Dezhou (CN)

(73) Assignee: **Zhongjin Dai**, Dezhou (CN)

(**) Term: **15 Years**

(21) Appl. No.: **29/844,968**

(22) Filed: **Jul. 1, 2022**

(51) LOC (14) Cl. **10-04**

(52) U.S. Cl.

USPC **D10/46.2**; D10/91

(58) Field of Classification Search

USPC D10/46.2, 46.3, 96, 101, 91;

D7/316-319, 543, 586, 376, 300, 629,

D7/608, 505

CPC G01F 19/00; G01F 19/002; B65D 41/26;

(57) **CLAIM**

The ornamental design for a scale, as shown and described.

DESCRIPTION

FIG. 1 is a front, top and right side perspective view of a scale, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate the portions of the scale, which form no part of the claimed design.

1 Claim, 7 Drawing Sheets
